ADJUSTABLE ACTUATING LEVER

William F. Dehn, Wauwatosa, Wis., assignor to Allen-Bradley Company, Milwaukee, Wis., a corporation of Wisconsin

Application September 8, 1955, Serial No. 533,072

4 Claims. (Cl. 74—522)

This invention relates to an adjustable actuating lever mechanism for rotatable control shafts, such as the control shaft for electrical limit switches; and resides more specifically in such a mechanism including an arm, a contact roller journaled on the outer end of the arm, and a clamp for clamping the arm to the control shaft with means permitting reversal of the arm end-for-end and face-for-face, and permitting angular adjustment between the clamp and the shaft, and permitting radial adjustment between the arm and the clamp, the radial adjustment being retained by cooperating ridges and indentations on clamp and arm which serve the additional function of indicating the effective length of the arm, and the angular adjustment being facilitated by means for steadyng the shaft against rotation during such adjustment.

Although designed primarily for use with, and although shown in use with, a rotary limit-switch, the invention is applicable to other types of devices actuatable by a rotatable shaft.

Devices of the general class to which the present invention is adapted, especially in the case of limit-switches, employ actuating levers of many different effective radial lengths, and of different axial location of the actuating roller carried by the lever, these differences being due to the requirements of the machines which the switches are designed to control. This necessitates the stocking of large numbers of alternative levers. Also frequently a slight, or even major, adjustment of throw becomes necessary in the course of building the controlled machine, and this requires either sending to the manufacturer for another lever, or altering the machine. Accordingly, the principal object of the present invention is to provide an actuating lever which can be adjusted and firmly held, with the actuating roller in any one of a plurality of radial and axial positions.

Actuating levers of the general class to which the present invention is adapted can be secured to the control shaft in an infinity of angular positions. But the fineness of angular adjustment is interfered with by the fact that the shaft of such switches must be effortlessly rotatable. Accordingly, a further object of the present invention is to provide simple means for steadyng the shaft during adjustment and during clamping the lever arm in adjusted position, and more specifically to design this means as compactly as possible.

A still further object of this invention is to provide a lever arm having a greater range of radial adjustment consistent with compactness.

A still further object is to provide that certain cooperating features of the clamping means and the lever arm shall perform the dual functions of clamping and of serving as index and scale to indicate the effective length of the adjusted arm.

A still further object is to generally improve the rigidity and simplicity of the mechanism.

These and other objects and advantages of the present invention are readily evident from the foregoing general

description and/or will appear from the description to follow.

In the following description, reference is made to the accompanying drawings, which constitute a part of this specification, and in which there is shown, by way of illustration but not of limitation, a specific form in which the invention may be embodied.

In the drawings:

Fig. 1 is an actual size diagonal front perspective showing of a switch with the present invention attached.

Fig. 2 is a similar perspective showing of the operating head and part of the contact base of such a switch with the actuating lever and associated parts removed.

All the remaining figures are double-size.

Fig. 3 is a front elevation of the block.

Fig. 4 is a rear elevation of the same.

Fig. 5 is a view of the same from beneath, viewed from the line 5—5 of Fig. 3 or Fig. 4.

Fig. 6 is a side view of the same, viewed from the line 6—6 of Figs. 3 and 6.

Fig. 7 is a front elevation of the actuating lever.

Fig. 8 is a rear elevation of the same.

Fig. 9 is a front elevation of the set screw which secures the block to the shaft, seen in the position which it occupies in Fig. 1.

Fig. 10 is a rear elevation of the plate.

Fig. 11 is a side elevation of the plate, viewed from the line 11—11 of Fig. 10.

Fig. 12 is a side elevation of the Allen-head screw which clamps the lever between the block and the plate.

Throughout the description, the same reference number is applied to the same member or to similar members.

Referring now to the drawings, more particularly to Figs. 1 and 2, it will be seen that 21 is the contact base 30 of a limit switch (i. e., the switch proper), and 22 is the operating head thereof. None of the internal details of these two assemblages is shown, inasmuch as such details are immaterial to the present invention. In fact, it is not necessary that the switch be a limit switch, although the present invention is primarily adapted for use with such a switch, it being sufficient that the switch be controllable by a rotatable shaft.

On the front face of operating head 22 is shown a bearing 23, which is immaterial to the present invention, 45 and through which protrudes the control shaft 24. On the protruding end of shaft 24, there is a screw-head slot 25, the object of which will be hereinafter described.

A block 26 is removably secured rigidly to the protruding end of shaft 24 in any appropriate manner, such 50 as the following. In a transverse hole 27 (see Fig. 6) is inserted set-screw 28 (see Fig. 9), which has a cut-away portion 29 and a threaded end 30. The cut-away portion registers with hole 31 in block 26 (see Figs. 3 and 4), and the threaded portion protrudes from transverse hole 27. With the cut-away portion thus registering, the end of shaft 24 is inserted in hole 31, and a nut 32 is screwed onto threaded portion 30. The tightening of this nut forces cut-away portion 29 of set-screw 28 slightly out of register with hole 31, thus locking block 26 securely against either sliding off shaft 24 or rotating with respect to shaft 24.

inasmuch as shaft 24 is very readily rotatable, it is necessary that some means be provided to keep it from rotating while block 26 is being secured thereto. 65 Otherwise block 26 and the actuating contact arm (to be hereinafter described) could not be finely secured in angular relation to the shaft. This holding means should be preferably some tool-engaging means, such as an Allen-head, knurled or polygonal sides, or (as shown) a screw-head indentation 25, capable of being engaged and held by a screwdriver. This screw-head indentation

is preferred, as taking up less space than the other alternatives.

The outer face of block 26 is designed to hold in radial adjustability an actuating contact arm 33 (see Fig. 1). These features are shown in Figs. 3 and 5, wherein outer ridges 34, and interrupted inner ridge 35-36, together constitute parallel guide means for arm 33. Each outer ridge and one side of the interrupted inner ridge define between them a groove 37 in which may slide one of the two parallel branches 38, into which arm 33 is bifurcated.

Turning now to Figs. 7 and 8, it will be seen that arm 33 is divided into these two parallel branches 38, joined together at the bottom by a bridge 39. On each face of each arm, there are laterally extending indentations 40, which perform the dual function of graduations, and of part of the means for cooperating with engaging means, all as will be more particularly described herein-after.

On one face at the opposite end of arm 33 from bridge 39, there is journaled, as at 41, an actuating contact roller 42, for the purpose of being engaged by a moving piece of machinery (not shown) to actuate the switch, in manner well known in the art.

Transversely in the bottom of grooves 37 of block 26, there are cooperating ridges 43, spaced so as to engage indentations 40 of arm 33.

Finally, there is a clamp-plate 44 overlying the face of block 26, and clampable thereto, with arm 33 between them, by means of screw 45, which is inserted through washer 46, hole 47 in clamp-plate 44, and threaded hole in block 26. The head 49 of screw 45 is provided with tightening means, such as Allen-head screw 50, as shown in Fig. 1.

Clamp-plate 44 (see Figs. 10 and 11) is provided with cooperating transverse ridges 51, spaced so as to engage indentations 40 of arm 33. It will be noted that these ridges 51 are located at the extreme upper and lower edges of plate 44; also that the lower edge of plate 44 is exactly aligned with the center of shaft 24. Accordingly, these edges perform the function of indexes for reading the graduations on arm 33.

In this connection plate 44 is provided with an opening 52, to engage the projecting end of shaft 24 (see Fig. 1). This opening serves the additional function of steadyng the plate against rotating about screw 45, and screw 45 steadies the plate against rotating about shaft 24.

Attention is also invited to the marking "34" and accompanying arrows, engraved on each face of arm 33, as shown in Figs. 7 and 8; and to the fact that the arm 33 is reversible end-for-end and face-for-face; and to the fact that in each of these four positions it is shiftable radially. The face-for-face reversibility permits changing the plane in which roller 42 operates, and this plane can be adjusted slightly further by giving a slight S-bend to that end of arm 33 which carries the roller. The end-for-end reversibility permits a considerable radial adjustability of the distance of roller 42 from the axis of shaft 24, with a lesser length of arm 33 than would otherwise be possible.

In any given radial position, regardless of face-to-face position, projections 43 on the face of block 26 engage graduations 40 on the back face of arm 33, and projections 51 on the back of plate 44 engage graduations 40 on the front face of arm 33, when the arm is firmly clamped between the plate and the block.

As shown, the graduations are at sixteenth inch intervals. The distance to the center of roller 42 from the nearest graduation is three-quarters of an inch; the length of plate 44 is likewise three-quarters of an inch.

Thus with the arm oriented as shown in Fig. 1, the radial distance from shaft center to roller center is equal to the graduation read by the upper edge of the plate plus an inch and a half. Or alternatively said radial distance can be determined by subtracting the graduation read by

the lower edge of the plate from three inches. The range is from $1\frac{3}{16}$ " to 3". As set in Fig. 1, the radial distance is $1\frac{3}{4}$ ".

With the block rotated 180° and the arm reversed end-for-end, the radial distance is equal to the graduation read by the upper end of the plate plus three-quarters of an inch. The range is from $\frac{3}{4}$ " to $2\frac{3}{16}$ ".

Without end-for-end reversibility, this combined range of from $\frac{3}{4}$ " to 3" could not have been obtained without shortening block 26 and plate 44, or lengthening arm 33.

Thus not only do the indentations and ridges cooperate to constitute part of the means for locking the arm in radial adjustment, but also the indentations serve as a graduated scale and the plate serves as an index for reading from this scale the effective length of the arm.

It will be seen that the present invention constitutes a new and useful calibrated, radially and angularly adjustable actuating lever for rotatable control shafts.

Now that one embodiment of the invention has been shown and described, it is to be understood that the invention is not to be limited to the specific form or arrangement of parts herein shown and described.

What is claimed is:

1. In a lever-actuated control mechanism having a rotatable shaft, the combination with said shaft, of: a block for rotation with the shaft; means for securing the block rigidly to the shaft; an actuating contact-arm carried by the block projecting therefrom radially with respect to the shaft, and adjustable radially with respect thereto; a clamp-plate overlying the face of the block; and means for clamping the clamp-plate to the block, to secure the arm rigidly between the plate and the block; wherein the block includes parallel guide-channels for the arm to slide in, and for preventing lateral movement of the arm with respect to the block; and wherein the block has a hole, in which the shaft is secured and through which the shaft projects beyond the face of the block; and wherein the clamping means is offset from the shaft; and wherein the plate has an opening for engaging the projecting end of the shaft, thereby steadyng the plate; and wherein the arm is bifurcated into two parallel branches, which straddle the clamping means and the projecting end of the shaft.
2. Mechanism according to claim 1; wherein there are evenly spaced indented transverse graduations on at least one face of both branches of the arm; and wherein there are cooperating transverse ridges on at least one of the backs of the clamp plate and the face of the block, the distance between successive ridges being an integral multiple of the distance between corresponding successive indented graduations.
3. Mechanism according to claim 2; wherein the indented graduations are on both faces of the arm; and wherein the ridges are on both the block and the plate; and wherein the arm is reversible face-for-face; and having an actuating contact-roller journally mounted on one face of the outer end of the arm.
4. Mechanism according to claim 3; wherein the arm is reversible end-for-end.
